(57) **CLAIM**

The ornamental design of a latch for electronic card faceplates, as shown and described.

DESCRIPTION

FIG. 1 is a perspective view of an embodiment of the latch showing our new design;

FIG. 2 is a top plan perspective view thereof;

FIG. 3 is a bottom plan view thereof;

FIG. 4 is a side view thereof; the opposite side being a mirror image;

FIG. 5 is a front view thereof;

FIG. 6 is a rear view thereof;

FIG. 7 is a perspective view of another embodiment of the latch showing our new design;

FIG. 8 is a top plan view thereof;

FIG. 9 is a bottom plan view thereof;

FIG. 10 is a side view thereof; the opposite side being a mirror image;

FIG. 11 is a front view thereof; and,

FIG. 12 is a rear view thereof.
